UNITED STATES PATENT OFFICE

153,910

DESIGN FOR A BOAT

Val K. Williamson, Phillipsburg, Ohio

Application August 8, 1947, Serial No. 140,782

Term of patent 14 years

(Cl. D71—1)

To all whom it may concern:

Be it known that I, Val K. Williamson, a citizen of the United States, residing at Phillipsburg, in the county of Montgomery, State of Ohio, have invented a new, original, and ornamental Design for a Boat, of which the following is a specification, reference being had to the accompanying drawing, forming a part thereof.

Fig. 1 is a top plan view of a boat, showing my new design; Fig. 2 is a side elevation of said boat; Fig. 3 is a front elevation of said boat; and Fig. 4 is a top perspective view as seen from a point to the rear of the boat.

I claim:

The ornamental design for a boat, as shown.
VAL K. WILLIAMSON.
